UNITED STATES PATENT OFFICE.

WALTER N. RAACH AND CLINTON E. SHURTLIFFE, OF GREENVILLE BOROUGH, PENNSYLVANIA, ASSIGNORS TO THE SHENANGO TIRE & RUBBER COMPANY, OF GREENVILLE, PENNSYLVANIA, A CORPORATION OF DELAWARE.

DESIGN FOR A TIRE.

Application filed August 13, 1920. Serial No. 403,403. Term of patent 3½ years.

To all whom it may concern:

Be it known that we, WALTER N. RAACH and CLINTON E. SHURTLIFFE, citizens of the United States, residing, respectively, at 117 South Mercer Street and at 81 Plum Street, in the borough of Greenville, county of Mercer, and State of Pennsylvania, have jointly invented a new, original, and ornamental Design for Tires, of which the following is a specification, reference being had to the accompanying drawings, forming a part thereof.

In said drawings, Fig. 1 is a sectional view of our new design; and Fig. 2 is a top plan view of a portion of a tire showing our new design.

We claim:

The ornamental design for a tire, substantially as shown.

WALTER N. RAACH.
CLINTON E. SHURTLIFFE.
